UNITED STATES PATENT OFFICE.

ROYAL D. TOMLINSON, OF NEW YORK, N. Y., ASSIGNOR TO ALLIS-CHALMERS COMPANY, OF MILWAUKEE, WISCONSIN, A CORPORATION OF NEW JERSEY.

CONDENSER.

No. 863,115.

Specification of Letters Patent.

Patented Aug. 13, 1907.

Application filed November 1, 1904. Serial No. 231,002.

To all whom it may concern:

Be it known that I, ROYAL D. TOMLINSON, a citizen of the United States, residing at New York, in the county of New York and State of New York, have invented certain new and useful Improvements in Condensers, of which the following is a specification.

My improvement relates to that part of a condenser system which mechanically assists in relieving the condenser of water and air in, either the surface or the jet 10 type.

In my Patent No. 724,972, I have disclosed means for delivering air from the condenser into the water delivery from the condenser so that the air delivery shall be subject to vacuum. This improvement contemplates a specific means for accomplishing the same 15 purpose.

The object of the invention is to produce a high vacuum in the condenser by avoiding the necessity of using a two-stage dry-air pump, independent of the 20 wet-air pump and yet attaining the same result as to vacuum by delivering from the single-stage dry-air pump into the wet-air pump between the plunger valves and the discharge valves.

Another object of the invention is to provide a water 25 packing for the dry-air pump trunk-piston.

Another object is to aerate the water from the condenser for use as feed water.

Another object is to provide small clearance in the wet-air pump by cutting off the induction port by the 30 plunger before completion of the stroke.

Another object is to deliver substantially all the air from the dry-air pump before water enters the wet-air pump on delivery side of the plunger.

The invention is best disclosed by reference to the 35 accompanying drawing forming a part of the specification and in which,—

The single figure is an elevation partly in section showing the condenser system.

The condenser 1 is either of the surface or the jet 40 type, and is conventionally shown, as the details thereof form no part of my invention. An air pipe 2 leads from the upper portion of the condenser and serves to remove the air which comes to the condenser in the steam. A pipe 3 leads from the lower portion of 45 the condenser and serves to remove the water from the condenser.

A dry-air pump 4 and a wet-air pump 5 are mounted, respectively, partially between the members of a pair of pedestals 6 bolted to a base-plate 7. Between the 50 two pairs of pedestals a steam engine 8 is mounted. The steam engine drives a main shaft at the top of the pedestals and upon the shaft are two fly wheels 9. The fly wheels bear external cranks and these connect respectively with the trunk-piston 10 of the dry-air

pump and the plunger 11 of the wet-air pump by the 55 usual connecting rods and piston rod. These connections are so designed that the dry-air pump trunk-piston is at the end of its stroke when the wet-air pump plunger is approximately at three-quarters of its stroke. In other words, the latter lags behind the former. 60 The wet-air pump is so designed as to have four times the capacity necessary to discharge the accumulating water. It therefore results that substantially all the air has been delivered by the dry-air pump to the wet-air pump before water enters the wet-air pump on the 65 delivery side of the plunger. But this result will be understood from the correlations of the parts.

The air exhaust pipe 2 leads from the condenser to the dry-air pump inlet. This inlet is controlled by the usual positively actuated inlet valve 12. The air 70 is delivered from the dry-air pump through the pipe connection 13, past check valves 14 and 15, to the wet-air pump through inlet port 16. This inlet or induction port is located so as to be cut off by the plunger 11 on its delivery stroke. The purpose of this 75 location is to reduce the clearance space. The plunger 11 has therein a series of valves that close during the delivery stroke. The plunger 11 forms a deck for these valves. A delivery valve deck 17 is located at the upper end of the wet-air pump 5. The valves 80 therein open during delivery stroke. An air chamber 18 is located upon the upper end of the wet-air pump cylinder 5 and is of reentrant form, the upper reentrant portion forming guides for the cross-head attached to the plunger rod. A discharge port 19 leads from the 85 lower part of the air chamber.

The pipe 3 connects from the lower portion of the condenser to a box 20 mounted upon the base plate 7. The chamber 21 within the box 20 is divided by a partition 22 forming the deck for the foot valves. The 90 wet-air pump 5 is mounted upon the box 20, and the cylinder is in free communication with the chamber 21. The dry-air pump cylinder 4 is surrounded by a water jacket 23 with the usual supply and discharge pipes. The jacket opens into the cylinder space circumferentially at porting 24, which forms a complete ring, and the water in the jacket comes directly in contact with the trunk-piston and serves to lubricate and pack the same and thus prevent leakage of air.

The operation is as follows: Power is derived from 100 the steam engine 8, and the wet-air pump 5 and the dry-air pump 4 are set into operation. Following a cycle of changes,—as the trunk-piston 6 of the dry-air pump 4 moves up on its suction stroke, the inlet valve 12 is positively opened by the valve gearing, check 105 valve 14 being held closed by a spring. Air from the condenser and pipe 2 is therefore drawn into the dry-air pump. Before the beginning of the delivery

stroke, the inlet valve 12 closes by its own weight. When the pressure in the pump exceeds that in the wet-air chamber 25, the check valves 14 and 15 are opened and the charge forced into said chamber. The 5 plunger 11 uncovers the port 16 at a position of the trunk-piston of approximately $\frac{1}{2}$ the stroke as shown at the line P on the drawing representing the lower plunger surface, but pressure of the air has not become excessive at this position of the trunk-piston, as the 10 air has been forced into the space within pipe connection 13. By the time the plunger 11 is about to uncover inlet port 16, a partial vacuum has been formed in the chamber 25, so that when the inlet port 16 is uncovered, the compressed air from the dry-air pump 15 opens the check valves 14 and 15, and the air passes to chamber 25, as just described.

The plunger 11 which lags approximately $\frac{1}{4}$ stroke with reference to the trunk-piston 10, will not normally reach the water in chamber 21, and the communicating space in cylinder 5, until $\frac{3}{4}$ stroke, for the reason that the wet-air pump is designed, as hereinbefore stated, of four times the necessary capacity. This position of parts is shown in the drawing. The plunger 11 is about to allow water to pass through its valves, 20 and the admission valve 12 is about to be opened for the up-stroke of the trunk-piston 10. This structure causes delivery of all the air for the stroke to the chamber 25 of the wet-air pump before water enters, so that the entire effect of the suction for the down-stroke can 30 be applied to aid the admission of air to the chamber 25. It is thus seen that in effect we have a two-stage air pump, the second stage of which is effected by the wet-air pump, besides serving the function of a wet-air pump. Moreover, as the plunger 11 descends during 35 approximately the last quarter of its stroke, the water is forced violently through its valves in the form of spray into the chamber 25 which has already received its full charge of air from the dry-air pump. This water, which is almost wholly devoid of air in 40 solution, will rapidly take up air in chamber 25, and thus become aerated in excellent condition to serve as feed-water. As this water is the result of condensation of steam, it is in a very pure state, and being devoid of air, it would seriously affect the boiler by attacking it chemically and would result in very rapidly pitting the same. By aerating this water as stated, the feed water is in better condition because it will not nearly so readily, or in fact not at all, attack the iron of the boiler. It is of course forced into the air 45 chamber 18 on the up-stroke of the plunger 11, and from thence is discharged through the discharge port 19 to the hot-well, not shown.

It is to be noted that the air in chamber 25 is not under much compression until after the inlet port 16 50 has been cut off. There is therefore not much useless compression of air into the space between the check valve 15 and the inlet port 16. By this means the

clearance is reduced to a minimum. It is also to be noted that there is no oil to mix with the water at any point. The apparatus is designed to operate with a 60 turbine, wherein no oil is necessary; but it may be used with any other engine. The dry-air pump trunk-piston is lubricated by water packing as described, and the wet-air pump plunger is sufficiently lubricated by the water pumped thereby. There is no necessity 65 of introducing oil for lubrication at any point, and thus the water delivered is kept free from oil and is thoroughly charged with air, and these two conditions place it in prime condition for use as boiler feed water.

In accordance with the provisions of the patent statutes, I have described the principle of operation of my invention, together with the apparatus which I now consider to represent the best embodiment thereof; but I desire it to be understood that the apparatus shown is merely illustrative and that the invention 75 can be carried out by other means.

What I claim as new and desire to secure by Letters Patent of the United States is:

1. In a condenser system, a dry-air pump including a discharge, a wet-air pump including an inlet, and a separate and independent inlet to the wet-air pump connecting from the discharge of the dry-air pump. 80
2. In a condenser system, a dry air pump, a wet air pump having an inlet, and discharge connections from the dry air pump to the wet air pump separate from and independent of the inlet to the wet air pump. 85
3. In a condenser system, a dry-air pump, a wet-air pump, and discharge connections from the dry-air pump to the chamber between the valve decks of the wet-air pump. 90
4. In a condenser system, a dry-air pump, a wet-air pump, and connections between the pumps arranged to discharge from the dry-air pump to the wet-air pump chamber between the discharge valve deck and the plunger. 95
5. In a condenser system, a wet air pump, having a water inlet connection to the condenser, a second inlet thereto for air from the condenser, a check valve in the second inlet, and means for cutting off the inlet space between the check valve and the pump. 100
6. A wet air pump cylinder having a water inlet connection to the condenser, a piston therefor, and a second inlet to the cylinder for air from the condenser, located to be cut off by the piston. 105
7. In a condenser system, a dry-air pump, a wet-air pump, means connecting the pumps, and a plurality of check valves in the connection. 110
8. In a condenser system, a dry-air pump, and a wet-air pump, the wet-air pump plunger lagging behind the dry-air pump piston. 115
9. In a condenser system, a dry-air pump, a wet-air pump, and operating means for the pumps constraining them to operate with the wet-air pump plunger lagging behind the dry-air pump plunger. 110
10. In a condenser system, a wet-air pump, a dry-air pump delivering to the wet-air pump, and means for spraying the admission of water in the wet-air pump. 115

In testimony whereof I affix my signature in presence of two witnesses.

ROYAL D. TOMLINSON.
